UNITED STATES PATENT OFFICE

WALTER K. VOSS, OF DAVENPORT, IOWA

AGITATOR

Application filed March 24, 1930. Serial No. 438,334.

The present invention relates to agitators and more in particular to a novel construction of agitator for washing machines or the like provided with a buoyant body portion. Among the objects of the present invention are to provide an agitator constructed of material of greater specific gravity than the washing fluid, but made buoyant by reason of the float chamber which allows the agitator to float as it oscillates and swishes the clothes through the washing fluid. The agitator is preferably constructed of metal or other suitable material of a greater specific gravity than the washing fluid in the tub in which it is operated.

A further object of the invention is to provide an agitator adapted to be automatically adjusted on the agitator shaft in accordance with the depth of the fluid in the washing machine tub. Another object is to provide a floating agitator construction adapted to be adjustably positioned upon an agitator shaft passing through the bottom of the tub.

A still further object of the invention is to provide an agitator adapted to be slidingly positioned upon the center pole or agitator shaft and readily and easily removed therefrom when desired. In order to allow for ready removal thereof, the agitator is provided with a handle member, which, when the agitator is being operated, is adapted to lie flat thereon and in no way cause inconvenience or hinder the agitator or the washing operation.

Further objects are to provide a construction of maximum simplicity, efficiency, economy, and ease of assembly, and such further objects, advantages, and capabilities as will later more fully appear and are inherently possessed thereby.

The invention further resides in the combination, construction and arrangements of parts illustrated in the accompanying drawing, and while I have shown therein a preferred embodiment, it is to be understood that the same is susceptible of modification and change, and comprehends other details, arrangements of parts, features and constructions, without departing from the spirit of my invention.

Referring to the drawing:

Fig. 1 is a view in vertical cross section through a washing machine tub and the novel construction of agitator.

Fig. 2 is a view in side elevation of the agitator construction.

Fig. 3 is a view in horizontal cross section taken on the line 3—3 of Fig. 1.

Referring more particularly to the drawing, the embodiment selected to illustrate the invention is shown as comprising a washing machine tub or the like 1 provided with a bottom 2, top 3, which is adapted to be provided with hinges or the like for permitting ready opening and closing of the tub, and an agitator or driving shaft 4 passing centrally through the bottom of the tub and extending to a position adjacent the top of the tub. This agitator shaft or center post is given an oscillatory movement by mechanism not disclosed, and in turn oscillates an agitator 5.

Seated upon the bottom 2 of the tub is a hollow pedestal 6 adapted to encompass the agitator shaft 4. Suitably mounted upon the agitator shaft and adapted to be rotated thereby, is a sleeve 7 provided with longitudinally disposed and oppositely spaced grooves or channels 8. These grooves or channels are adapted to receive longitudinally extending ribs 9 on the hub 10 of the agitator. This construction permits the agitator to bodily slide on the sleeve 7 for changing its position to give the maximum washing efficiency.

The hub portion 10 is provided with an enlarged downwardly projecting skirt or annular flange 11 on which are formed or connected a plurality of arms or spokes 12 provided at their ends with relatively narrow and vertically extending blades or impelling members 13. Formed integrally with or connected to these blades or impelling members at their upper inner edges is an annular ring 14 for strengthening and giving rigidity to the agitator structure. The skirt portion 11 prevents clothing or other material in the tub from being caught intermediate the sleeve 7 and hub 10 of the agitator.

The arms or spokes 12 along with the inner edges of the blade or impelling member 13

and the annular ring 14 and skirt 11 of the hub, forms a housing or confining means for housing and seating an annular container or float chamber 15. As shown more clearly in Fig. 1, this annular container or float is constructed of thin sheet metal and provided with an air space sufficient to make the entire agitator buoyant. An upper frame or spider 16 is adapted to be mounted over the float 10 chamber and prevent ready removal thereof. This frame or spider has the end portions 17 of the radiating arms 18 thereof, connected by means of screws or the like 19 to the annular ring 14 at the point where the same is formed with or connected to the blades or impelling members 18.

The entire agitator structure is slidable on the sleeve 7 and may be lifted therefrom whenever it is desired. In order to permit its ready removal, the agitator is provided with a handle member 20, which, when the agitator is being operated, is adapted to lie flat thereon and in no way cause inconvenience or hinder the agitator or the washing 25 operation.

By reason of the present construction, the entire agitator shifts with the amount of washing fluid that is in the tub. This shifting of the agitator is taken care of automatically by the floating chamber, and thus a maximum washing efficiency is always secured. From the above description and disclosure, it will readily be seen that I have provided a novel construction of agitator 35 which is admirably adapted for washing machines and the like.

Having thus disclosed my invention,
I claim:

1. An agitator for washing machines and the like provided with a driving shaft, comprising a sleeve on said shaft, an impeller adapted to be shifted upon said sleeve and provided with a hub portion, arms radiating from said hub portion, impelling blades at the extremity of said arms, and a buoyant chamber associated with said impeller for automatically adjusting the height of the same in accordance with the depth of washing fluid in the machine.
2. An agitator for washing machines and the like provided with a driving shaft, comprising a sleeve on said shaft, an impeller adapted to be shifted upon said sleeve and provided with a hub portion, arms radiating from said hub portion, impelling blades at the extremity of said arms, an annular ring connecting said blades, and a buoyant chamber positioned upon said arms and within said ring and blades for automatically adjusting the height of the same in accordance with the depth of washing fluid in the machine.
3. An agitator for washing machines and the like provided with a driving shaft, comprising an impeller slidable on said shaft and

provided with a hub portion, arms radiating from said hub portion, impelling projections at the extremity of said arms, and a float member associated with said impeller for adjusting the height thereof in accordance with the depth of the washing fluid. 70

4. An agitator for washing machines and the like provided with a driving shaft, comprising an impeller provided with a hub portion, arms radiating from said hub portion, impelling projections at the extremity of said arms, an annular ring connecting said projections, a float member positioned on said arms and hub portions and within said annular ring, and a frame for the upper portion of said member for preventing ready removal thereof from the impeller. 75

5. An agitator for washing machines and the like provided with a driving shaft, comprising an impeller provided with a hub having a skirt portion, arms radiating from said hub, impelling blades at the outer ends of said arms, an annular ring connecting said projections, a float member positioned on said arms and hub portions and within said annular ring, and a frame for the upper portion of said member for preventing ready removal thereof from the impeller. 80

6. An agitator for washing machines and the like provided with a driving shaft, comprising a sleeve on said shaft, an impeller adapted to be shifted on said sleeve and provided with a hub having a skirt portion, arms radiating from said skirt portion, blades at the extremity of said arms, and buoyant means for permitting floating of said impeller in said washing fluid, said skirt preventing clothes that are being washed from being caught intermediate the impeller and sleeve. 95

7. An agitator for washing machines or the like provided with a driving element passing through the bottom of the tub comprising, in combination, an impelling member having a sliding and non-rotative connection with said element and arranged to be slide upwardly from and downwardly onto said element to disassemble or to assemble the parts, said member including a frame, a buoyant chamber supported thereby, oppositely disposed and upwardly projecting lugs on said frame, and a handle pivotally secured to said lugs to traverse said impelling member and to lie flat upon the upper surface of said buoyant chamber while the machine is operating. 105

8. An agitator for washing machines or the like provided with a driving element passing through the bottom of the tub comprising, in combination, a buoyant impeller mounted on said driving element for sliding movement relative thereto, said parts being so arranged that said impeller may be withdrawn over the end of the shaft when articles are to be placed in the tub, a handle on said impeller for removing said impeller from 110

said element, and means connecting said handle to said impeller for relative movement from an operative position to an out-of-the-way position extending adjacent to the surface of said impeller.

In witness whereof I hereunto subscribe my name to this specification.
